TAPERED I-BEAM FOR DIVING BOARDS AND THE LIKE

Melvin M. Tilley, La Canada, Calif., assignor to Kaiser
Aluminum & Chemical Corporation, Oakland, Calif.

Filed Feb. 11, 1971, Ser. No. 114,750

Term of patent 14 years

Int. Cl. D25—99

U.S. Cl. D13—1

FIG. 1 is a perspective view of the I-shaped beam of my invention;

FIG. 2 is an enlarged end elevational view of the beam of FIG. 1, as taken along line 2—2 thereof;

FIG. 3 is another enlarged cross-sectional view of the beam of FIG. 1, as taken along line 3—3 thereof;

FIG. 4 is a further enlarged cross-sectional view of the beam of FIG. 1, when taken along line 4—4 thereof;

FIG. 5 is an enlarged fragmentary plan view of the top of the beam of FIG. 1; and

FIG. 6 is an enlarged fragmentary plan view of the bottom of the beam of FIG. 1.

I claim:

The ornamental design for a tapered I-beam for diving boards and the like, substantially as shown and described.
